UNITED STATES PATENT OFFICE.

DUDLEY S. SEYMOUR, OF OAK PARK, ILLINOIS, ASSIGNOR TO UNION SPECIAL MACHINE COMPANY, OF CHICAGO, ILLINOIS, A CORPORATION OF ILLINOIS.

TRIMMING MECHANISM FOR SEWING-MACHINES.

1,400,998.

Specification of Letters Patent. Patented Dec. 20, 1921.

Application filed March 10, 1916. Serial No. 33,299.

To all whom it may concern:

Be it known that I, DUDLEY S. SEYMOUR, a citizen of the United States, residing at Oak Park, in the county of Cook, State of Illinois, have invented certain new and useful Improvements in Trimming Mechanism for Sewing-Machines, of which the following is a description, reference being had to the accompanying drawing and to the figures 10 of reference marked thereon.

The invention relates to new and useful improvements in trimming mechanisms for sewing machines and more particularly to a trimming mechanism wherein the trimming 15 blades operate in a substantially horizontal plane.

An object of the invention is to provide a trimming mechanism of the above character wherein the fixed blade is mounted on 20 the presser foot and the movable blade co-operating therewith is directly mounted on an oscillating vertical shaft located in rear of the presser bar. The vertical shaft being capable of movement up and down with 25 the presser bar and also of endwise movement independent of the presser bar for holding the trimming members in co-operative relation with each other.

A further object of the invention is to 30 provide a trimming mechanism of the above character wherein the vertical shaft is oscillated by an oscillating sleeve mounted on the presser bar which oscillating sleeve receives its movements from the same train of 35 mechanism which vibrates the needle bar.

A further object of the invention is to 40 provide a trimming mechanism of the above character wherein the vertical shaft supporting the movable trimming blade operates as a guide bar for the presser bar.

These and other objects will in part be 45 obvious and will in part be hereinafter more fully described.

In the drawings, which show by way of 45 illustration, one embodiment of the invention:

Figure 1 is a view partly in section and partly in side elevation, showing a portion of a sewing machine having the improved 50 trimming mechanism applied thereto;

Fig. 2 is a vertical sectional view through the forward end of the overhanging arm showing a portion of the operating devices for the trimming mechanism;

Fig. 3 is a view partly in plan and partly in section showing the presser foot and the trimming blades, the strip guard showing in part and turned to one side;

Fig. 4 is a sectional view on the line 4—4 of Fig. 1;

Fig. 5 is a sectional view on the line 9—9 of Fig. 1;

Fig. 6 is a sectional view on the line 6—6 of Fig. 1;

Fig. 7 is a vertical sectional view showing a portion of the presser bar, the sleeve surrounding the same, the eccentric for oscillating the trimmer and showing the manner of supporting the sleeve in the lower bearing for the presser bar; and

Fig. 8 is a detail partly in section showing the manner of preventing the presser bar from oscillating and the tension spring for the same.

The improved trimming mechanism consists of a fixed blade attached to the presser foot and a movable blade which co-operates with said fixed blade. This movable blade is carried by an arm connected directly to a vertical shaft arranged in rear of the presser 80 bar, said shaft being yieldingly pressed downwardly to hold the blades in co-operative relation. The vertical shaft together with the trimming blades will be free to move up and down, therefore, with the 85 presser foot. This vertical shaft is oscillated by a sleeve which surrounds the presser bar. Said sleeve carries an eccentric which is connected through suitable devices to the vertical shaft and imparts oscillation there- 90 to. The sleeve in turn is oscillated by a train of mechanism from the shaft which drives the needle bar.

Referring more in detail to the drawings:

I have shown the invention as applied to 95 a sewing machine having a work support 1 which is preferably in the form of a suspended cylindrical arm. Said machine is also provided with an overhanging arm terminating in a head 2 at the forward end 100 thereof, in which is mounted a needle bar 3. Said needle bar is provided with needles 4 and suitable complementary stitch forming devices are located in the work support 1 and co-operate with the needles.

Mounted in suitable bearings in the overhanging arm is a shaft 5 which may be oscillated in any suitable way. This shaft 5

carries an arm 6 which is connected by a link 7 to a lug formed on a collar 8 clamped to the needle bar by a suitable clamping screw.

The presser foot 9 is mounted on the 5 presser bar 10. This presser bar is carried by the head 2. Said presser foot is provided with needle slots 11 which receive the needles 4. Said presser foot at its forward end is formed with a slot 12 adapted to receive the upturned edges of the fabric sections, which edges are to be trimmed and subsequently abutted and then presented to the stitching mechanism. Said presser foot is formed with a recess to receive the fixed 10 blade 13 of the trimming mechanism. Said blade is clamped in the recess by a plate 14 held in place by a clamping screw 15. The cutting edge of the fixed member 13 is substantially in line with one side face of the 15 slot 12. Coöperating with this fixed blade or member 13 is a movable blade 16. Said blade is mounted on an arm 17 which arm is fixed to the lower end of a vertical shaft 18 by a screw 19. The vertical shaft 18 is 20 mounted in bearings 20 and 21 formed in the head 2. Said shaft is freely mounted in the bearings and is moved downwardly by a spring 22. This spring at its lower end bears against the arm 17, while the upper 25 end of the spring bears against a washer 23 seated in a recess 24 in the lower face of the bearing 20. The vertical shaft 18 at its upper end passes freely through a threaded sleeve 25. This sleeve is threaded in the 30 bearing 21 and may be moved up and down in said bearing. The presser bar 10 is provided with a rearwardly projecting arm 26 which is clamped to the presser bar by a suitable screw 27. This arm is formed with 35 an opening 28 through which the vertical shaft 18 freely passes. Said arm 26 is formed with an annular recess 29 which receives an inverted cup 30. The shaft 18 also freely passes through this inverted cup. 40 A spring 31 rests on the upper face of the inverted cup and bears at its upper end against the sleeve 25. This spring 31 normally forces the arm 26 downwardly, and this arm being rigid with the presser bar 45 yieldingly holds the presser foot against the work supporting arm 1. The vertical shaft 18 becomes a guide bar for the presser bar 10 and prevents the presser bar from oscillating in its supporting bearings as a result 50 of the trimming action. The vertical shaft 16, however, is not under tension except from the spring 22 which moves the same downwardly and holds the movable trimming blade in contact with the fixed trimming blade. As the presser foot is raised or lowered, the vertical shaft 18 will move the same. The tension of the presser-bar spring 31 may be increased by moving the 55 threaded sleeve 25 downwardly in the supporting bearing 21 and the tension may be 60

decreased by a reverse movement of the threaded sleeve.

Projecting laterally from the shaft 18 is an arm 32 which carries a ball stud 33 on its outer end. A sleeve 34 surrounds the 70 presser bar 10 and said sleeve extends through the lower bearing 35 formed in the head 2 for the presser bar 10. A collar 36 secured to the lower end of the sleeve holds the same from upward movement through 75 the bearing, and a shoulder 37 formed on the sleeve holds the same from downward movement through the bearing. On the upper end of the sleeve there is an eccentric 38. An eccentric strap 39 coöperating with this 80 eccentric 38 engages the ball stud 33 so that as the eccentric 38 is oscillated the shaft 18 will be in turn oscillated. This eccentric 38 has its outer face transversely curved and fits a similarly curved recess in the eccentric 85 strap so that the outer end of the eccentric strap may move up and down without disturbing its connection with the eccentric. This is to permit the vertical shaft 18 to move up and down with the presser bar 90 without interfering with its connection with the sleeve 34 which does not have a vertical movement.

The sleeve 34 is provided with an arm 40. The shaft 5 carries a second arm 41. This 95 arm 41 is connected by a link 42 to one arm of a rock lever 43. The rock lever 43 is mounted on suitable cone bearings 44 and 45. The cone bearing 45 is preferably formed integral with a supporting stud 46 which extends through a thickened portion 47 of the overhanging arm 48 of the machine. Said stud is clamped to the overhanging arm by a nut 49. The outer cone bearing 44 is adjustable and is held in adjusted positions by a nut 50.

The arm 52 of the rock lever extends downwardly and is connected by a link 53 to the arm 40. As the shaft 5 oscillates, the arm 41, through the link 42 will oscillate the rock 100 lever 43 and this rock lever, through the link 53, will oscillate the sleeve 34 and the shaft 18 and the shaft 18, in turn, will oscillate the movable trimming member.

From the above description, it will be apparent that I have provided a trimming mechanism wherein the movable blade is oscillated from a vertical shaft located in rear of the presser bar, which vertical shaft can be moved up and down with the presser bar 115 and yet is free from tension except such as is necessary to hold the blades in proper trimming relation. The vertical shaft carrying the trimming blade is also oscillated by a compact train of mechanism supported in part by the presser bar and said mechanism is driven from the operating devices which 120 actuate the needle bar so that the entire trimmer operating mechanism is located in the supporting head at the forward end of the 125 130

overhanging arm and consists of a comparatively short train of devices. This provides an efficient trimmer operating mechanism wherein there is little or no undesirable vibrations in the operating parts.

It is obvious that minor changes in the details of construction and arrangement of parts, may be made without departing from the spirit of the invention, as set forth in the 10 appended claims.

Having thus described my invention, what I claim as new and desire to secure by Letters Patent, is:—

1. A trimming mechanism for sewing machines including in combination a work support, a presser foot having a needle opening therethrough, a presser bar supporting said presser foot, a stationary trimming blade carried by said presser foot in advance of said 20 needle opening, said presser foot having a guiding slot formed therein extending from its extreme front end rearwardly toward said needle opening, said stationary blade being positioned so that its cutting edge is in line 25 with one wall of said guiding slot, a vertical shaft having its axis in rear of the axis of the presser bar, a movable trimming blade carried by said shaft and coöperating with said stationary blade, and means for oscillating 30 said vertical shaft.

2. A trimming mechanism for sewing machines including in combination a work support, a presser foot having a needle opening therethrough, a presser bar supporting said 35 presser foot, a stationary trimming blade carried by said presser foot in advance of said needle opening, said presser foot having a guiding slot formed therein extending from its extreme front end rearwardly toward 40 said needle opening, said stationary blade being positioned so that its cutting edge is in line with one wall of said guiding slot, a vertical shaft having its axis in rear 45 of the axis of the presser bar, a movable trimming blade carried by said shaft and coöperating 50 with said stationary blade, means for yieldably moving said vertical shaft endwise for holding said blades in coöperative relation, and means for oscillating said vertical shaft.

3. A trimming mechanism for sewing machines including in combination a work support, a presser foot, a presser bar supporting said foot, a stationary trimming 55 blade carried by said presser foot, a vertical shaft in rear of the presser bar, the movable trimming blade carried by said shaft and coöperating with said stationary blade, a sleeve surrounding said presser bar, means 60 for supporting said sleeve whereby the same may be oscillated but is held from endwise movement relative to the presser bar, means for oscillating the sleeve, and means whereby said sleeve oscillates said vertical shaft.

65 4. A trimming mechanism for sewing

machines including in combination a work support, a presser foot, a presser bar supporting said foot, a stationary trimming blade carried by said presser foot, a vertical shaft in rear of the presser bar, the 70 movable trimming blade carried by said shaft and coöperating with said stationary blade, a sleeve surrounding said presser bar, means for supporting said sleeve whereby the same may oscillate but is held from 75 endwise movement relative to the presser bar, means for oscillating the sleeve, an eccentric carried by said sleeve, an eccentric strap coöperating therewith, an arm carried by said vertical shaft to which said 80 eccentric strap is connected and means for oscillating said sleeve.

5. A trimming mechanism for sewing machines, including in combination, a work support, an overhanging arm having a supporting head at its outer end, a shaft mounted in the overhanging arm and extending into said supporting head, a vertical shaft carried by said supporting head, a movable blade carried by said vertical shaft, a rock 90 lever located in said head, means for oscillating the rock lever from the first named shaft extending into the head, an oscillating member, means for oscillating said member from said rock lever, and devices operated 95 by said oscillating member for oscillating said vertical shaft.

6. A trimming mechanism including in combination, a work support, an overhanging arm, a supporting head at the outer end of said overhanging arm, a needle bar mounted in said head, a shaft mounted in said overhanging arm and extending into said supporting head for reciprocating said 100 needle bar, a presser foot, a presser bar 105 carrying said presser foot, a stationary trimming blade carried by the presser foot, a movable trimming blade coöperating with the stationary blade, a vertical shaft on which said movable blade is mounted, a rock 110 lever mounted in said supporting head, an arm carried by the first-named shaft, a link connecting said arm to said rock lever, and devices operated by said rock lever for oscillating the vertical shaft carrying the 115 trimmer blade.

7. A trimming mechanism including in combination, a work support, an overhanging arm, a presser foot, a presser bar carrying said presser foot, a trimming mechanism including a stationary trimming blade and a movable trimming blade, a vertical shaft carrying said movable trimming blade, said vertical shaft being mounted in bearings in rear of the presser bar, a spring surrounding said shaft carrying the movable trimming blade, an arm carried by the presser bar and arranged to be engaged by said spring whereby the spring yieldingly holds the presser foot on the work support, 125 130

and a second spring surrounding said vertical shaft carrying the movable trimming blade and operating to yieldingly move said shaft downwardly for holding the movable trimming blade in contact with the stationary blade.

8. A trimming mechanism including in combination a work support, an overhanging arm, a presser foot, a presser bar carrying said presser foot, an arm mounted on the presser bar and projecting rearwardly therefrom, said arm having an annular groove formed therein, an inverted cup seated in said groove, a shaft extending vertically through said arm and cup and free to move therethrough, a movable trimming

blade carried by said shaft, a spring surrounding said shaft and bearing at one end against said cup, and a threaded sleeve having an opening through which said shaft extends, said sleeve bearing against the upper end of said spring for placing the same under tension and holding the presser foot yieldingly in contact with the work support.
